CASKET RETAINING DEVICE FOR HEARSE

Filed Oct. 1, 1926

UNITED STATES PATENT OFFICE.

WILLIAM B. PARSELS, OF PLEASANTVILLE, NEW JERSEY.

CASKET-RETAINING DEVICE FOR HEARSE.

Application filed October 1, 1926. Serial No. 138,930.

This invention relates to hearses, and particularly to means associated with a hearse for retaining a casket against movement longitudinally of the hearse; and the said invention is of great utility when installed in a hearse having means for preventing lateral movement of the casket therein, such means being described and claimed in a patent to this applicant numbered 1,565,195 and dated December 10, 1925.

When a hearse is provided with means for preventing lateral movement of a casket therein, such as mentioned in the foregoing paragraph, the present invention acts in conjunction therewith to prevent any movement of the casket with relation to the floor of the hearse, but, of course, this present invention may be utilized without reference to the patented device mentioned and it will operate satisfactorily to prevent shifting of the casket, and it will be effective without liability of marring the finish of the casket.

It is a further object of this invention to produce a casket retainer which cannot be displaced by vertical strain or pressure on the retaining device, except when the retaining devices are manipulated for the purpose of dislodging the holder.

It is a still further object of the invention to produce a device of the character indicated which will be neat in appearance, inexpensive as to installation and capable of performing the functions satisfactorily.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a sectional view of a body of a hearse, showing the floor and a device embodying the invention applied thereto;

Figure 2 illustrates an enlarged sectional view longitudinally of the floor, omitting the side of the hearse;

Figure 3 illustrates a transverse sectional view of a fragment of the movable casket retaining device; and

Figure 4 illustrates a detail view of one of the rollers.

In these drawings, 5 denotes the floor of the hearse, 6 an end post, 7 rollers for supporting the casket and provided with shoulders 8 which are intended to be partially imbedded in the bottom of the casket for preventing lateral movement thereof, and 9 denotes the outline of the casket to show the relation of the casket to the supporting rollers and the invention. The caskets are usually provided with moldings or beadings 10 at their lower edges, and when a casket is delivered to a hearse, it rides on rollers such as 7 and is supported clear of the floor of the hearse by such rollers. A retaining block or bumper 11 has an end seated in a recess or socket 12 formed in the floor of the hearse, and the said bumper may be anchored to the post 6 by a fastening 13, such as screws or the like. The inner face of the element 11 is shaped to form a seat 14 for a cushion 15, preferably of felt or some compressible material, which will yield with the pressure of the molding or beading of the casket in order that the finish of the casket will not be impaired by reason of its being held at the front end of the hearse. It is shown in Fig. 2 that the bottom edge of the casket fits in the seat and hence the casket cannot move vertically when so seated.

The embodiment of the invention here illustrated as the most satisfactory means for retaining the casket seated with respect to the element 11, comprises a channel iron 16 preferably seated in a longitudinally disposed recess 17 formed in the floor of the hearse, the upper edge of the channel iron being on a plane below the peripheries of the rollers on which the casket is supported as it is pushed into or removed from the hearse. The channel iron and preferably the floor thereunder is provided with coinciding pairs of apertures 18 and 19, respectively, the apertures of each pair diverging, for a purpose to be presently explained.

The casket retaining device is in the nature of a chock block which engages the rear end of the casket and retains it in proper position with relation to the front casket engaging element. As shown herein, the chock block 105 comprises a base 20 which is slideable in the channel iron and it extends above the side flanges of the channel iron and fits under the bottom of the casket which is elevated with respect to the floor of the hearse. Preferably 110

2

a pad or cushion 21 of rubber is inserted in the base and projects slightly from its upper face into engagement with the bottom of the casket and it presents a friction surface which aids in retaining the casket in place. A standard 22 rises or extends upwardly from the base 20 and it is provided with a diagonally disposed threaded aperture 23, in which a screw 24 is threaded, which screw 10 may be manipulated for projecting or retracting the said screw with relation to a clamping plate 25. The clamping plate may have a recessed boss 26 in which the end of the screw is seated for maintaining the parts 15 in operative relation. The clamping plate is flexible and has a cushioned face 27 which is pressed into engagement with the bead or flange of the casket, or when the screw is retracted, the resilient plate springs out of engagement with the casket. By the means 20 just stated, the clamping plate is forced into engagement with the casket or the base flange thereof, and when the block is properly anchored, the casket will be held against 25 movement.

The base of the chock block has diagonally disposed apertures 28 and 29 which may be caused to align with apertures of the channel iron, and the said coinciding apertures 30 are intended to receive the securing pins 30 and 31, respectively, which anchor the block in place. Owing to the fact that the securing pins diverge with relation to each other, the lower ends of the said pins are separated, 35 as compared with their upper ends or heads and they produce a wedging action and a resistance to vertical displacement when they are properly seated in their apertures.

Of course the casket could be held against 40 lateral movement by ordinary pins such as are now used in hearses, although better results are attained through the use of the rollers.

I claim:

45 1. A hearse having panel posts, a casket retaining element in the front end of the hearse, a block, means for securing the block at the rear of the casket, and means on the block adjustable to embrace a part of the upper surface of a molding of the casket for 50 clamping it in place.

2. A hearse having panel posts, a casket retaining element in the front end of the hearse, a block, a guide on the floor of the hearse in which the block is movable, the said block and guide having diverging apertures extending downwardly, securing pins in the said apertures of the block and apertures of the guide, and a clamp adjustable 55 on the block for engaging a part of a casket.

60 3. A hearse having panel posts, a casket retaining element on one of the posts in the

front end of the hearse, a block having a pair of diverging downwardly directed apertures, a guide on the floor of the hearse 65 for said block having a plurality of pairs of apertures with which the apertures of the block may align, securing pins in the said apertures of the block and in selective apertures of the guide, and a clamp on the block 70 adjustable with relation to a casket for embracing an edge of the casket.

4. A hearse having panel posts, a casket retaining element on one of the posts in the front end of the hearse, a block for retaining the rear end of the casket, said block including means for holding it at different positions of adjustment in the hearse, a flexible plate having one end anchored to the block, a cushioning element on the face of the plate, 80 a screw threaded in a portion of the block and bearing against the plate for pressing it toward a casket with the cushion in engagement with said casket.

5. A hearse having panel posts, a casket retaining element in the front end of the hearse, rollers rotatable with relation to the floor of the hearse having means engaging the bottom of a casket for preventing lateral movement thereof, a block for retaining the rear end of the casket, said block including means for holding it at different positions in the hearse, a flexible plate having one end anchored to the block, a cushioning element on the face of the plate, a screw threaded 95 in a portion of the block and bearing against the plate for pressing it toward the casket with the cushion in engagement with said casket.

6. A hearse having panel posts, a casket retaining element on one of the posts in the front end of the hearse, rollers rotatable with relation to the floor of the hearse having means engaging the bottom of a casket for preventing lateral movement thereof, a block, 100 means for securing the block at the rear of the casket, and means on the block adjustable to embrace a portion of the casket for clamping it in place.

7. A hearse having panel posts, a casket retaining element on one of the posts in the front end of the hearse, rollers rotatable with relation to the floor of the hearse having means engaging the bottom of a casket for preventing lateral movement thereof, a block, 110 a guide on the floor of the hearse in which the block is movable, the said block and guide having diverging apertures extending downwardly, securing pins in the said apertures of the block and apertures of the guide, 115 and a clamp adjustable on the block for engaging a part of the casket.

WILLIAM B. PARSELS.
